UNITED STATES PATENT OFFICE.

THEODORE S. WILKIN, OF MILWAUKEE, WISCONSIN.

SAW-MILL HEAD-BLOCK.

SPECIFICATION forming part of Letters Patent No. 311,701, dated February 3, 1885.

Application filed October 24, 1884. (No model.)

To all whom it may concern:

Be it known that I, THEODORE S. WILKIN, of Milwaukee, in the county of Milwaukee and State of Wisconsin, have invented certain new and useful Improvements in Saw-Mill Head-Blocks, of which the following is a specification.

This invention relates to saw-mill set-works; and it consists in novel devices for adjusting the knee upon and independently of the head-block for taper sawing or like purposes, and securing the knee at the required point.

In the accompanying drawings, Figure 1 is a side elevation, partly broken away to show the operating parts; Fig. 2, a transverse section on the line *x x* of Fig. 1; Figs. 3 and 4, like views showing a modified form of shifting or adjusting mechanism; Fig. 5, a detail view.

I may here remark that this lever mechanism for moving the knee upon and independently of the head-block is not of itself new in either of the forms shown; but the two forms more commonly in use are illustrated for the purpose of showing the adaptation of my improvements to different shifting mechanism.

A indicates a head-block supported upon sills B B of the usual truck, which truck is ordinarily provided with two or with three head-blocks and their attendant parts.

C indicates a sliding knee, having lateral ribs or flanges *a*, which travel in grooves *b* in the head-block and guide the knee in its movements back and forth.

Within the lower part of the knee C, and projecting below the same, is a rack-bar, D, having grooves *e* in its sides to fit the guiding ribs or ways *d* of the knee, (shown in Fig. 2,) said bar being provided with teeth *e* from end to end in its under side, and with similar teeth, *f*, for a suitable distance on its upper side. The rack-bar is arranged directly over and meshes with a pinion, E, on the main or common setting shaft F, the rotation of which pinion causes the rack and the knee to be moved jointly forward or backward, as may be required. When, however, it becomes necessary to saw logs or beams tapering, one or more of the knees of the carriage requires to be moved forward or backward of the line of a given knee, which ordinarily is not made in-

dependently adjustable. This adjustment is effected by a lever, G, pivoted in the knee and connected by a link, H, with the rack-bar D, as in Fig. 1, or fashioned into a toothed segment at its lower end, and made to mesh with teeth on the upper face of said rack-bar, as in Fig. 3, both plans being now in common use.

To hold the lever G in the position to which it may be moved, and thereby to lock the knee and the rack-bar firmly together and prevent independent or relative movement, it has hitherto been customary to provide a notched or recessed arc, and to furnish the lever with a locking-bolt to enter the notches or recesses thereof when not held therefrom. Such arrangement adds to the cost of construction and occupies space which it is desirable to leave clear. I therefore provide the locking device or mechanism illustrated in Figs. 1 and 3, consisting of a toothed rack-bar, I, pivoted in the knee and adapted to engage with the teeth *f*. So long as the latch-bar I remains in engagement with rack-bar D the knee and rack-bar will be firmly locked together; but if the latch-bar be raised out of engagement the knee may be moved independently of the rack, which latter, being in engagement with pinion E, cannot move except as the pinion is rotated. The latch-bar is arranged to fall by gravity and engage with the teeth *f* of the rack-bar, and to render its action quicker and more certain I add a spring, J, which presses down upon the latch-bar and prevents accidental disengagement.

I preferably employ a spiral spring, its lower end encircling a stud, *g*, on the latch-bar, and its upper end similarly encircling a stud, *h*, on the threaded plug K, which is screwed into an opening in the upper side of the knee C, and formed with a polygonal head to receive a wrench or like tool, by which the plug may be turned up or down for removal or insertion or to vary the pressure of the spring. This arrangement permits a new spring to be applied or the old one to be adjusted at any time without dismounting the knee.

To raise the latch-bar when necessary, I provide the lever G with a pivoted L-shaped hand-piece, L, from the angle of which a rod, M, is carried down and attached to a laterally-projecting arm, *i*, of the latch-bar I, which

extends outward through a slot or opening, *j*, in the side of the knee *C*, as shown in Figs. 2 and 4.

When it is desired to move the knee independently of the rack-bar, it is only necessary to grasp the upper end of lever *G* and the hand-piece or small lever *L*, which will both be grasped with one hand, move the lever *G* forward or backward in the direction required and to the proper distance, and then release the hold, whereupon the latch-bar *I* will drop into engagement with the teeth *f* of rack-bar *D*, thereby locking the parts in proper relative positions.

15 It will be seen that the above arrangement alone permits no independent adjustment of knee for any distance less than one tooth *f*; hence it is important that some other means be provided for finer adjustments to secure 20 perfect alignment of the knees of a saw-mill carriage. For this purpose I provide for the latch-bar *I* an eccentric pivot, *k*, Figs. 1, 3, and 5, which has a throw or eccentricity equal to the space of one of the teeth *f*, and which, 25 being rotated in its bearings in the knee, will move the latter independently of the rack-bar *D* any distance desired up to the limit of its throw.

The eccentric pivot *K* is provided at one end 30 with a clamping or binding nut, *l*, or may be otherwise held against rotation after proper adjustment, and it is formed with a polygonal head, *m*, to permit it to be readily turned by a wrench or like tool. The lever *G* is formed 35 with a horizontal cylindrical portion, which is journaled in the knee, as shown, the upright arm of the lever, as also rod *M*, being at the side of the knee, as shown in Figs. 2 and 4, so as to avoid any opening in the upper side of 40 the knee, through which chips or sawdust might enter and clog the teeth of the rack-bar and latch.

It is obvious that the latch-bar may be pivoted to the rack-bar and its free end arranged 45 to engage with the sliding knee, such arrangement being merely a reverse of that shown and described.

Having thus described my invention, what I claim is—

50 1. In combination with a head-block, a rack-bar movable in relation to said head-block, a knee adjustable independently of the rack-bar, a latch for locking the knee and rack-bar together, said latch being pivoted to one of said parts and adapted to engage with the other, and a shifting-lever fulcrumed in the knee and connected with the rack-bar, substantially as shown and described.

2. The combination, substantially as herein described and shown, of a head-block, a setting rack-bar provided with teeth on opposite sides, a setting-pinion meshing with one set of said teeth, a knee adjustable independently of the rack-bar, and a toothed latch-

bar pivoted to the knee, adapted to engage 65 with the second set of teeth thereof and to lock the knee to the rack and prevent independent movement of the knee or rack in either direction.

3. The combination of a head-block, a setting rack-bar provided with teeth on its upper and lower sides, a setting-pinion meshing with the teeth of one side, a knee adjustable independently of the rack-bar, a latch-bar pivoted to the knee and adapted to engage 75 with the teeth of the other side of the rack-bar, and a shifting-lever fulcrumed in the knee and connected with the rack-bar, substantially as described and shown.

4. The combination of a head-block, a setting rack-bar provided with teeth on opposite faces, a setting-pinion meshing with the teeth of one face, a knee adjustable independently of the rack-bar, a latch-bar pivoted to the knee and adapted to engage with the second 85 set of teeth of the rack, a shifting-lever fulcrumed in the knee and connected with the rack-bar, substantially as described and shown, and a hand-piece pivoted to the shifting-lever, connected with and serving to lift the latch-bar out of engagement with the rack.

5. The combination of a head-block, a setting rack-bar, a knee adjustable independently of the rack-bar, a latch-bar adapted to lock the rack-bar and knee together and prevent 95 independent movement in any direction, and a spring bearing upon said latch and serving to hold it in engagement with the rack, substantially as set forth.

6. The combination of a head-block, a rack-bar movable in relation thereto, a knee adjustable independently of the rack-bar, a latch-bar adapted to lock the knee and rack-bar together, said latch-bar being pivoted to one of said parts and adapted to engage with the other, a spring bearing upon said latch-bar, and an adjustable screw-plug bearing upon the spring, substantially as described and shown.

7. The combination of a head-block, a rack-bar, and a knee adjustable independently of the rack-bar, a latch adapted to lock the knee and rack-bar together, and an adjustable pivot for the latch, substantially as and for the purpose set forth.

8. The combination of a head-block, *A*, a sliding rack, *D*, an independently-adjustable knee, *C*, a latch-bar, *I*, adapted to lock the knee and rack-bar together, said latch-bar being attached to one of said parts and adapted to engage with the other, and an eccentric pivot, *k*, for said latch-bar, provided with a clamping or binding device, substantially as shown and described.
